DESIGN FOR A BOX OR SIMILAR CONTAINER

Louis A. Trevisan, Bloomfield, N. J., assignor to American Can Company, New York, N. Y., a corporation of New Jersey

Application June 13, 1939, Serial No. 85,477

Term of patent 7 years

To the Commissioner of Patents:

Be it known that I, Louis A. Trevisan, a citizen of the United States of America, residing at 65 First Avenue, in the city of Bloomfield, county of Essex and State of New Jersey, have invented a new, original, and ornamental Design for a Box or Similar Container, of which the following is a specification, reference being had to the accompanying drawing, forming a part thereof.

lar container embodying my new design, the view showing the cover in closed position;

Fig. 2 is a front elevational view of the box shown in Fig. 1; and

Fig. 3 is a side elevational view of the box showing the cover in partially opened position.

I claim:

The ornamental design for a box or similar container, as shown and described.

LOUIS A. TREVISAN.
